FUEL FEEDING SYSTEM

Gordon L. Tescher, Anderson, Ind., assignor to
Tesch Corporation, Anderson, Ind.

Application December 30, 1949, Serial No. 136,072

6 Claims. (Cl. 123—139)

1

This invention relates to new and useful improvements in fuel feeding systems and particularly to fuel feeding systems for internal combustion engines.

It is an object of this invention to provide a simplified fuel feeding system for internal combustion engines.

It is a further object of this invention to provide a fuel feeding system which will not create an unduly high back pressure on the engine.

It is an object of this invention to provide a simplified fuel feeding system which is particularly adapted for use with two cycle internal combustion engines.

A further object of this invention is to provide a fuel feeding system for those types of internal combustion engines wherein light weight and the minimum number of moving parts is of prime consideration.

Another object of the present invention is to provide a fuel feeding system in which the fuel is pumped to the carburetor by utilizing the positive and negative pressures generated in the engine crankcase by the piston head.

Still another object of the present invention is to provide a fuel feeding system having a fuel pump which is positioned directly on the outer wall of the engine casing for direct communication with the crankcase and operated by the alternating positive and negative crankcase pressures of the engine, thus eliminating connecting conduits and weighty and complicated operating linkages.

Still another object of the present invention is to provide a fuel feeding system wherein the fuel is delivered to the carburetor by the fuel pump at a predetermined, uniform, maximum pressure regardless of the speed of the engine.

Another object of the present invention is to provide a fuel feeding system wherein the fuel pump is provided with a spring biased, by-pass means which relieves pressure on the engine carburetor when a predetermined maximum fuel pressure has been reached.

Another object of this invention is to provide a fuel feeding system wherein the fuel from the fuel pump is delivered to an auxiliary gravity tank above the carburetor, this reserve tank having overflow and by-pass means communicating with the main fuel tank for the purpose of relieving excess pressure in the carburetor and controlling the amount of fuel in the auxiliary tank by returning excess fuel lifted by the pump to the main tank, said auxiliary tank also providing a starting supply of fuel.

2

Another object of this invention is to provide a simplified and improved diaphragm fuel pump principally for use in fuel systems of internal combustion engines but which may be adapted to any application wherein it is desired to pump a fluid by means of pulsating fluid pressures.

With the above and other objects in view, as will be presently apparent, the invention consists in general of certain novel details of construction and combinations of parts hereinafter fully described, illustrated in the accompanying drawings and particularly claimed.

In the accompanying drawings, like characters of reference indicate like parts in the several views, and:

Fig. 1 is a side elevational view, partly in section and partly broken away, showing the simplified and basic form of the fuel feeding system forming the present invention, the same being used in conjunction with a standard one cylinder, two cycle gasoline engine,

Fig. 2 is a cross-sectional view taken on the line 2—2 of Fig. 1,

Fig. 3 is a side elevational view, partly in section and partly broken away, showing a modified form of fuel feeding system as applied to the same type of engine, and

Fig. 4 is a cross-sectional view taken on the line 4—4 of Fig. 3.

In Figs. 1 and 2 of the drawings are shown the simplified and basic form of the fuel feeding system of the present invention.

In the design and construction of the small two cycle gasoline engine the governing factors are lightness, simplicity, compactness and the need for the minimum number of moving parts. It is apparent, then, that the invention as shown in Figs. 1 and 2 of the drawing is of special importance in the art due to its simplicity.

With the exception of that portion of the cylinder wall upon which the fuel pump is mounted, the engine shown herein is of standard construction.

Referring now to Fig. 1, the numeral 10 designates the cylinder head of the engine and the reference numeral 11 the crankcase thereof. Reciprocating within the cylinder head 10 is the piston head 12 and linking the piston head 12 to the crank shaft 13 are the piston rod 14 and wrist pin 14b. Cast into the lower side portion of the cylinder head is an elongated channel 15 which leads from the exhaust port 16 in the cylinder bore to an exterior opening 17 for exhausting the products of combustion to the atmosphere.

Cast into the upper side of the cylinder head 10

3

is an elongated channel 18 which connects an aperture 19 in the crankcase with an intake port 20 in the cylinder bore. On the outer end of the crankcase 10 is the standard carburetor 21 which discharges into the crankcase thru the aperture 22. At the inner end of the cylinder head is the standard sparkplug 23.

The fuel tank of the engine is represented by the numeral 24 and leading to the intake side of a fuel pump 26 is the conduit 25. A conduit 25b carries the fuel from the exhaust side of the fuel pump to the carburetor 21.

For seating the fuel pump 26, the face of the cylinder head casting exterior of the elongated channel 18 is formed with a planar and generally circular face 27 which is machined to a smooth surface. Concentrically placed in the face 27 and communicating with the elongated channel 18 is a relatively large circular aperture 28.

The fuel pump 26 is formed of three circular sections, the lowermost section being designated by the reference numeral 29. This disc shaped lower section 29 has a planar lower face 30. The upper face 31 is planar for a short distance inwardly from its peripheral edge and then drops downwardly in the form of a circular, concave depression 32. At the center of the section 29 is formed a small hole 33, the lower part thereof having an enlarged bore as at 34 to form a shoulder, the purpose of which will be later described. Spaced on either side of the vertical axis of the lower section 29 and extending thru said section are a pair of ports 35.

Overlying the lower section 29 and of the same diameter as the section is an elastic diaphragm 36. Transfixing the center of the diaphragm 36 is a bolt 37, the upper end of which is reduced in diameter to form a shoulder 38, and the upper end of said reduced section being threaded to receive a nut 39. Between a shoulder 38 and the nut 39 are clamped the diaphragm 36 and two clamping washers 40. The lower end of the bolt 37 has fastened thereon, by a cotter pin or any other suitable means, a washer 42. Positioned on the bolt 37 above the lower washer 42 and seated in the enlarged bore 34 is a coil spring 43 which resists compression and which, when the diaphragm 32 is moved upwardly by a pressure pulse, returns it to a neutral position when the pulse has passed.

Immediately overlying the diaphragm 36 in clamping relation with the lower section is a disc-shaped intermediate circular section 44 of the same diameter as the lower section 29. The lower face of said intermediate section has concentrically formed therein a vertical walled chamber 45 of sufficient depth to permit clearance of the diaphragm assembly when it is moved upwardly its maximum distance by the crankcase pressure.

Overlying the intermediate section 44 and of the same diameter is a disc-shaped top section 46, and between the sections is placed a gasket 47. For drawing the sections of the pump together into fluid tight relationship there are provided near the peripheral edge of the disc sections a set of spaced bolts 48, the lower ends of which threadedly engage internally threaded sockets in the lower section 29. For securing the pump to the machined face 27 and also to aid in drawing the pump sections into a fluid tight seal are the spaced bolts 49, which are threaded at their lower ends to engage internally threaded sockets 50 in the cylinder casing.

In order to receive and discharge fuel, inlet 75

4

and outlet chambers 51 and 52 are provided, these being relatively deep, approximately semi-circular recesses having vertical side walls, the portion of the top section 46 between the recessed chambers 51 and 52 forming a rib 53 separating the two chambers. On either side of the rib 53 and thru the side wall of the top section 46 are threaded openings 54 and 55. In the opening 54 is positioned the end fitting 56 of the pump supply conduit 25 and in the opening 55 is positioned the end fitting 57 of the discharge conduit 25b. In order to provide fluid passage from the inlet chamber 51 to the diaphragm chamber 44, a port 58 is formed in the intermediate section 44. Over the lower end of this port 58 and secured to the intermediate section 44 in any suitable manner is a flap valve 59. A similar port 60 leads from the diaphragm chamber 44 to the outlet chamber 52 as shown, and over the upper end of said port is a flap valve 61 secured in any suitable manner.

While the inlet and outlet valves 59 and 61 are herein shown to be flap valves it is to be understood that any form of spring biased valve may be used and still have suitable operation of the pump.

In order to describe the operation of the fuel feeding system it is necessary to briefly outline the operation of the two cycle engine shown in the drawings.

As shown in Fig. 1, the piston 12 has just reached the top of its stroke, and compressed a charge of atomized fuel and air in the cylinder head. At this point the charge is fired by the sparkplug 23. The piston 12 moves outwardly toward the crankcase 11 and in so doing compresses the air and gaseous fuel mixture in the crankcase. This pressure likewise builds up in the elongated channel 18. When the piston moves far enough to uncover the ports 16 and 20, the products of combustion pass thru the exhaust port 16, channel 15 and exterior opening 17. At the same time pressure in the channel 18 forces a fresh charge into the cylinder head. The piston at this point reaches the bottom of its stroke and moves inwardly covering the ports. As the piston progresses inwardly it forms a partial vacuum in the crankcase 11 and channel 18, this negative pressure causing a fresh mixture of air and gaseous fuel to be drawn into the crankcase. The engine is then ready for a new firing stroke.

It will thus be noted that the channel 18 is subject to alternate positive and negative pressure pulses, the positive pulse greatly exceeding the negative pressure.

When a negative pressure occurs in the channel 18 the space below the diaphragm is also evacuated and the diaphragm moves downwardly. This reduces the pressure in the inlet chamber 51 and fuel is forced by atmospheric pressure up the fuel supply line 25 and into the inlet chamber 51, the flap valve 59 moving downwardly to permit the fuel to flow into the upper diaphragm chamber 45. When the heavy positive pressure pulse occurs in the channel 18 the diaphragm assembly moves upwardly compressing the fuel in the upper diaphragm chamber 45 and also compressing the coil spring 43. The flap valve 59 is then forced into closed position and the flap valve 61 is opened, the pressure forcing fuel into the outlet chamber 52 and thru the conduit 25b into the carburetor 21. As the pressure is relieved, the coil spring 43 returns the diaphragm assembly to neutral position and a negative pulse then draws it downwardly.

It may be noted that in this form of the invention the engine must be turned over a number of times mechanically or a charge must be mechanically placed in the carburetor so that the engine will operate until air in the fuel feeding system has exhausted and fuel reaches the carburetor. It may be further noted that the pressure in the fuel feed line to the carburetor increases approximately in direct ratio to the engine speed.

The extreme simplicity of this form of the invention is to be emphasized, no moving parts other than the diaphragm being required, with the complete elimination of all pump actuating cams and gears. This extreme simplicity is highly desirable in some engine applications.

In Figs. 3 and 4 of the drawings are shown a modified form of the invention, incorporating a pressure relief valve in the fuel pump 26 wherein when a predetermined maximum pressure has been reached in the outlet chamber of the fuel pump, the valve will open, relieving the pressure into the fuel inlet chamber. Also shown for use, if desired, is an auxiliary gravity fuel tank, but it is to be emphasized that the modified fuel pump may be used without the auxiliary gravity tank.

In the modified form shown in Figs. 3 and 4 all parts of the construction not modified are indicated by the reference numerals designated above.

The modification of the fuel pump consists of changes made in the circular top section now designated by the reference numeral 46a. As in the previous form the top section has formed therein the inlet chamber 51a and outlet chamber 52a with the rib 53a separating the two chambers. In the side walls of the top section 46a and on either side of the rib 53a, axially aligned at right angles to said rib, are the threaded ports 54a and 55a. The threaded port 54a is enlarged, as shown, to receive the threaded bushing 54b, for a purpose hereinafter described. Threaded in the bushing 54b is the end fitting 56a of the fuel conduit 25.

Axially aligned with the ports 54a and 55a and in the rib 53a is a threaded opening 62. Positioned in this opening is a pressure relief valve designated in general by the reference numeral 63.

The valve 63 consists of a tubular body portion 64 having one end outwardly threaded as at 65. This end of the tube 64 is also provided with a reduced bore 66 which terminates inwardly in a spherical recess 67 forming a seat for a ball 68. The opposite end of said tube is closed with the exception of the relatively small slotted opening 69. This end of the tube is slotted as at 70 to provide a means for rotation of the tube for removal, said slot being aligned with the opening 69. A coil spring 71 of predetermined strength is compressed between the ball 68 and the opposite end of the tube. It will thus be seen that if the bushing 54b is removed a turning tool may be inserted thru the opening 54a for removal of the valve 63.

Between the outlet chamber 52a and the carburetor, if desired, may be placed the auxiliary gravity tank 72. The conduit 25c entering the bottom of the tank has an upwardly directed extension 74. Also from the bottom of the tank 72 extends a return tube 74 which empties into the top of the fuel tank 24. This tube 74 has an upwardly directed extension 75 which reaches nearly to the top of the tank 72. A

conduit 76 connects the bottom of the gravity tank to the carburetor 21.

In operation the modified system has several advantages if simplicity is not the primary factor. Those familiar with the art will appreciate that it is desirable not to maintain a pressure greater than necessary to supply the engine with adequate quantities of fuel, since any excess of pressure produces unnecessary and undesirable back pressure on the automobile engine. When the pressure in the outlet chamber 52a exceeds the maximum desirable and for which the coil spring 71 has been duly calibrated, the ball 68 will be forced from its seat, the fuel under pressure escaping thru the tubular body portion 64 and slotted opening 69 into the inlet chamber, the valve closing when the pressure drops.

If the gravity tank 72 is used it will be seen that there will be available at the time of starting a small supply of fuel to feed to the carburetor which will serve until the pump begins to move fuel into the auxiliary tank. The fuel line 74 and its extension 75 serve as an overflow return means to the main tank 24 in case the pump 26 delivers an excess of fuel. This bypass return also prevents accumulation of pressure in the carburetor and the by-pass valve 63 then serves only as a release for excess pressure in the outlet chamber 52 if it builds up more rapidly than it can be relieved by the fuel line 25c.

While the present fuel feeding system in its preferred form is shown as applied to a one cylinder, two cycle engine, it is to be understood that it could be applied with minor changes in the system or in the engine design to multiple two or four cycle internal combustion engines, without departing from the spirit and scope of the invention as claimed.

What is claimed is:

- 40 1. In a fuel feeding system for internal combustion engines and in combination with an engine, a fuel tank, a fuel pump associated with said engine and operated by alternating positive and negative pressures in the crankcase thereof, and conduit means for carrying fuel from the fuel tank to said pump and from the pump to the carburetor of the engine, said fuel pump having spring biased, by-pass valve means associated therewith whereby fuel pressures in excess of a predetermined maximum at the outlet of said pump will be relieved to the inlet side of said pump to thereby prevent the accumulation of excessive pressures in the carburetor of the engine.
- 45 2. In a fuel feeding system for internal combustion engines and in combination with an engine, a fuel tank, a diaphragm fuel pump associated with said engine and operated by alternating positive and negative pressures in the crankcase thereof, and conduit means for carrying fuel from the fuel tank to said pump and from the pump to the carburetor of the engine, said fuel pump having spring biased, by-pass valve means associated therewith whereby fuel pressures in excess of a predetermined maximum at the outlet of said pump will be relieved to the inlet side of said pump to thereby prevent the accumulation of excessive pressures in the carburetor of the engine.
- 50 3. In a fuel feeding system for internal combustion engines and in combination with an engine having an opening in the wall thereof, a fuel tank, a diaphragm fuel pump mounted directly on the wall of said engine in fluid tight relationship therewith and positioned over said
- 55
- 60
- 65
- 70

opening, said pump being in communication with the crankcase of said engine whereby alternating positive and negative pressures in the crankcase actuate the diaphragm of the fuel pump for the pumping of fuel, and conduit means for carrying fuel from the fuel tank to said pump and from the pump to the carburetor of the engine, said fuel pump having spring biased, by-pass valve means associated therewith whereby fuel pressures in excess of a predetermined maximum at the outlet of said pump will be relieved to the inlet side of said pump to thereby prevent the accumulation of excessive pressures in the carburetor of the engine.

4. In a fuel feeding system for internal combustion engines and in combination with an engine, a principal fuel supply tank, a fuel pump associated with said engine and operated by alternating positive and negative pressures in the crankcase thereof, an auxiliary gravity fuel tank positioned so as to be above the carburetor of the engine and holding a relatively small amount of fuel, conduit means for carrying fuel from the principal fuel supply tank to the fuel pump, conduit means for carrying fuel from the fuel pump to the auxiliary fuel tank, conduit means from said auxiliary fuel tank to the carburetor of the engine and an overflow and return conduit means having an opening positioned near the top of said auxiliary fuel tank and leading into the top of the principal fuel supply tank for relieving excess fuel and pressure produced in said auxiliary fuel tank by the fuel pump.

5. A fuel feeding system as set forth in claim 4 wherein said fuel pump has a spring biased, by-pass valve means associated therewith whereby fuel pressures in excess of a predetermined maximum at the outlet of said pump may be relieved to the inlet side of said pump thereby to prevent the accumulation of excessive pressures in the carburetor of the engine.

6. In a fluid pressure operated pump, a lower circular disc having a recess in the upper face thereof and at least one aperture therethrough for admission of an operating fluid; an intermediate circular disc of the same diameter as

and immediately overlying said lower disc and having a circular recess in the lower face thereof and a pair of spaced apertures providing fluid passage from said circular recess to the upper face of said disc; a flexible pumping diaphragm clamped between said lower and intermediate circular discs; a flap valve attached to the upper face of said intermediate disc and overlying one of said spaced apertures and a second flap valve positioned over said second spaced aperture and attached to the upper wall of the recess in said intermediate circular disc; an upper circular disc of the same diameter as and overlying said intermediate circular disc and having a pair of arcuate recesses formed in the lower face thereof and spaced so as to leave a separating partition, thereby forming the upper and side walls of separate fluid inlet and outlet chambers, each of said chambers having a fluid access opening in one of said walls; and means for simultaneously securing said overlying discs in fluid tight relationship, said separating partition having a threaded aperture therein, a tube having an exteriorly threaded open end engaged with said aperture and a spring biased valve element within said tube and normally closing said open end, the opposite closed end of said tube having a slotted opening formed transversely thereof to thereby serve both as a fluid access to the valve and a tool engaging slot for seating or removing the valve structure.
